United States Patent Office.

EDWARD HOLDEN, OF LAUREL MOUNT, BAILDON, NEAR LEEDS, ENGLAND.

Letters Patent No. 98,966, dated January 18, 1870.

IMPROVEMENT IN APPARATUS FOR COMBING AND PREPARING WOOL, &c.

The Schedule referred to in these Letters Patent and making part of the same

To all to whom it may concern:

Be it known that I, EDWARD HOLDEN, of Laurel Mount, Baildon, near Leeds, in the county of York, England, have invented "Improvements in Apparatus for Preparing Wool or other Fibres;" and I do hereby declare that the following is a full and exact description thereof, reference being had to the accompanying drawings, and to the letters of reference marked thereon:

In preparing wool or other fibre by mechanical means, it has been customary to operate upon such fibre by passing it through series of separate apparatus, each apparatus being furnished with a single set of bars of gill-combs. By thus working, the whole accumulation upon the apron of one apparatus is, in a mass, fed into the succeeding one, which I have found to be objectionable; and the object of my invention is to operate more effectively upon the fibre, and at the same time to reduce the number of operations upon it, by passing it through apparatus arranged to effect a draught on such fibre between sets of gill-combs, and I employ drawing-rollers as the means of effecting such draught between the sets of screw-gill teeth. The gill-teeth, receiving the fibre from such drawing-means, will, as occasion requires, be speeded to effect draught.

Drawing-rollers are also applied to receive the fibre from the last of the gill-teeth, and in passing from these last drawing-rollers, the fibre may be received on to an apron, or into cans, as desired. Aprons are used with the drawing-rollers.

But that the invention may be better understood, I will, by the aid of the accompanying drawing, proceed to describe means pursued by me in carrying the same into effect.

Description of the Drawings.

Figure 1 shows a longitudinal section,

Figure 2, a side view, and

Figure 3, a plan view of apparatus, arranged to carry out my improvements.

In each of the views, the same letters indicate corresponding parts.

A A indicate the main framing.

a is the feed-apron, on which the fibre to be operated upon is laid, and by which it is conducted to between the rollers b b, and thence to the first set of gill-combs c, by which it is partially opened or straightened, as is well understood.

The fibre carried forward by these combs c is thence taken between the drawing-rollers d d, and by the increased speed of these rollers, as compared with that of the combs c, it is drawn or straightened. The fibre thence passes to the combs e, which are caused to travel at a speed greater than that of the rollers d d, by which it is further opened out or straightened.

From the combs e it is conducted to the delivery-rollers f f and apron g.

Motion is given to the various parts, according to the arrangement shown, in the following manner:

B is the main or driving-axis, which is supported, as shown, on suitable bearings, carried by the main framing A, and it receives motion from a steam-engine, or other suitable power, acting, by a strap or band, upon a pulley, B', affixed on that axis B.

Upon this axis B is also affixed the pulley C, which, by a strap or band, C', gives motion to the pulley D affixed on the shaft or axis D', which is also supported to revolve in suitable bearings carried by the main framing A.

Upon the shaft or axis B is also affixed the toothed wheel E, the teeth of which take into the teeth of the wheel F affixed to the shaft F', which is supported freely to revolve in bearings carried by the main framing, and upon this shaft F' are affixed the bevelled pinions F² and the pinion G.

The teeth of the bevelled pinions F² take into the teeth of the bevelled pinions F³ affixed on the lower of the screw-shafts F⁴, for giving motion to the gill-bars e, while they are in the lower tier.

Upon these lower screw-shafts F⁴ are also affixed pinions F⁵, the teeth of which, in the ordinary manner, take into the teeth of pinions F⁶ affixed on the upper of the screw-shafts.

F' and F⁶ are guides to guide the gill-bars e in their respective motions from the upper to the lower tier, and from the lower to the upper tier.

The teeth of the wheel G take into the teeth of the intermediate wheel G¹, the teeth of which take into the teeth of the wheel G², affixed on the axis f¹ of the lower roller f, so as to give the desired motion to that roller.

Upon the axis f¹ is also affixed the pinion G³, the teeth of which take into the teeth of another pinion, G⁴, affixed on the axis of the roller G⁵, serving, in part, to support and give motion to the upper belt or apron G⁶.

g¹ g² are other supporting-rollers to the belts g and G⁶, supported in bearings capable of adjustment by means of the screws g³ g⁴, as shown.

The pressure exerted by the upper of the rollers f is regulated by means of the springs f¹ and adjusting-screws f².

Upon the shaft or axis D' is also affixed the pinion D², which, by means of the intermediate pinion D³, gives motion to the wheel D⁴ affixed on the shaft or axis D⁵, upon which are affixed the bevelled pinions D⁶ D⁷, the teeth of which take into the teeth of the bevelled pinions D⁸ affixed on the lower of the screw-shafts D⁹, for giving motion to the gill-bars e, while they are in the lower tier.

Upon the shafts D^8 are affixed the pinions D^9 , the teeth of which take into the teeth of pinions affixed on the upper screw-shafts D^{10} , for giving the requisite motion to the bars c , while they are in the upper tier.

D^{11} and D^{12} are guides to the gill-bars c , in their movement to and from the respective tiers.

Upon the shaft or axis D^5 are also affixed the pinions H and I .

The teeth of the pinion H take into the teeth of a pinion, H^1 , which, with a bevelled pinion, H^2 , affixed thereto together, are capable of turning on a fixed stud, H^3 .

The teeth of the bevelled pinion H^2 take into the teeth of the bevelled pinion H^4 affixed on the shaft H^5 , which is supported to revolve in adjustable bearings H^6 , and has formed on it the worm H^7 , which receives the teeth of the screw-wheel H^8 affixed on the axis b' of the lower roller b , and gives the requisite motion to those rollers b .

Upon the axis b' is also affixed the pinion J , which, by means of the intermediate pinion J^1 , gives motion to the pinion J^2 on the axis of one of the supporting-rollers d' of the feed-apron a .

The pinion I , by means of the intermediate wheels $I^1 I^2$, gives motion to the pinion I^3 affixed on the axis d' of the lower roller d , to give motion to that roller.

The pressure of the upper roller d is regulated by springs d^2 and screws d^3 , acting on its bearings.

In operating upon English wool, I find it useful for the speed of the rollers d to be about three times that of the combs e , and for the speed of the combs e to be about three times that of the rollers d ; but these speeds may be considerably varied to the class or character of fibre for the time under operation, as will readily be understood by persons in the habit of working wool and other fibres requiring to be operated upon by gill-combs.

The pitch of the screws, or otherwise the means employed for giving the progressive motion to the respective sets of gill-combs, may correspond one with the other, or be varied, as will also be readily understood.

Having thus described my invention, and means which I adopt in carrying the same into effect, I would have it understood that

What I claim, is—

The combination, with two sets of screw-gill combs $c e$, of the set of intermediate drawing-rollers $d^1 d^2$, the whole arranged and operating substantially as and for the purposes specified.

In testimony whereof, I have signed my name to this specification, in the presence of two subscribing witnesses.

EDWARD HOLDEN.
